UNITED STATES PATENT OFFICE.

FRANK HAYES, OF SUPERIOR, WISCONSIN.

DRIVING-GEAR.

SPECIFICATION forming part of Letters Patent No. 548,311, dated October 22, 1895.

Application filed November 30, 1894. Serial No. 530,404. (No model.)

To all whom it may concern:

Be it known that I, FRANK HAYES, a citizen of the United States, residing at Superior, in the county of Douglas and State of Wisconsin, have invented certain new and useful Improvements in Driving-Gear; and I do hereby declare the following to be a full, clear, and exact description of the invention, which will enable others skilled in the art to which it applies to make and use the same.

My invention relates to various new and useful improvements in bicycles, and particularly to certain novelties in the construction of the gearing of the same.

The objects of my invention are to produce an improved gearing for bicycles by which the power applied can be varied within wide limits, and wherein I am enabled to vary the power almost instantly and without dismounting from the machine.

My improved device is composed of comparatively few parts, is strong and rigid in construction, and does not add materially to the weight of the machine, while at the same time it may be economically manufactured and easily applied to existing bicycles of the safety type.

Broadly considered, my invention consists in applying a sprocket-wheel on each side of the main frame adapted to be partially rotated by means of levers and the center of rotation of which may be varied with the result of changing the working radius of the wheel, according to the power which is to be applied, it being obvious from the following description that when the working radius of the sprocket-wheels is decreased the power to be applied to the driving-wheels will be increased proportionately. The means whereby the working radius of these sprocket-wheels may be varied are subordinate to the broad and generic invention; but I have devised, and will hereinafter describe and claim an improved device for effecting this end, which I have experimented with in practice and which fulfills all conditions.

For better comprehension of my invention attention is directed to the accompanying drawings, forming a part of this specification, and in which—

Figure 1 is a side elevation of a bicycle with my improvements applied thereto. Fig.

2 is a plan view partly in section, of the driving-gear, on an enlarged scale. Fig. 3 is an elevation, partly in section, of the same; Fig. 55 4, a transverse sectional view of the same; and Fig. 5 an enlarged elevation, partly in section, of the rear sprocket-wheel, showing an improved form of clutch for the same.

In all the different views corresponding parts are designated by the same figures of reference.

The bicycle illustrated in Fig. 1, to which my improved driving-gear is applied, is of a conventional type, being provided with a front 65 wheel 1, a rear wheel 2, the diamond frame 3, the cross parts 4, the seat 5, and the handlebar 6.

While my driving-gear can be conveniently applied to a machine of this type, it is to be understood that I do not limit myself to the same, as I find my present improvements can be made use of with all kinds of safety and other bicycles, including tricycles and polycycles. The axle of the rear driving-wheel is 75 provided on each side thereof with a sprocket-wheel 7 of the usual construction, with which the sprocket-chain 8 engages, said sprocket-chain being passed around and operated on each side by the sprocket-wheel 9, forming 80 part of my improved driving-gear. The sprocket-wheels 7 are loosely mounted on the axle of the rear wheel and are provided, preferably, on the outside with an integral drum 10. Within this drum are lugs 11, four of 85 said lugs being shown in Fig. 5, and 12 are pawls mounted on pins 13 and bearing against said lugs, whereby the thrust of said pawls would be received. 14 is a ratchet-wheel 90 keyed to the axle of the rear driving-wheel 2 and mounted within the frame 10. Small leaf-springs 15 are made use of to keep the said pawls 12 engaged with the periphery of the ratchet-wheel 14. By means of a clutch of the character just described and which is clearly 95 shown in Fig. 5, the sprocket-wheel 7, when rotated in the direction of the arrow, will turn the driving-wheel through the pawls 12 and ratchet-wheel 14; but when moved in an opposite direction the said pawls will travel over the periphery of said ratchet-wheel without affecting the driving-wheel.

The sprocket-chains 8 are of the usual construction, except that instead of being con-

tinuous throughout their length they are provided with a heavy coiled spring 16, as shown, and by means of which the said sprocket-chains will accommodate themselves to the different positions of the sprocket-wheels 9, irrespective of any increase of working radius.

17 is a bearing or drop-forging, which is inserted, preferably, within the lower end of the tubular cross-brace 4 and brazed therein so as to form a part of the machine. This bearing 17 is provided with two short horizontal journals 18, extending to each side thereof. The outer ends of these journals 18 are turned down a trifle to form a shoulder against which 15 the cone 19 on each side faces, said cones being of ordinary construction. One of the rear braces of the machine 20 on each side is provided with an eye at its end, which is also inserted over the end of the journals 18, and 20 it is held in place thereon by the nut 20', which holds the parts securely in place. Each journal 18 is screw-threaded, as shown, and is provided on such portions with the adjustable cones 21 of ordinary construction.

25 22 is a cylindrical hub, mounted on the cones 19 and 21 on hard-steel balls 23, whereby a well-known form of ball-bearing is obtained. Small annular rings 24 serve to hold the balls 23 in place when the hub 22 is removed from the journal.

25 is a square flange which is formed on the hub 22, and to which flange is bolted the operating-lever 26, carrying an ordinary pedal 27 at its outer end. Mounted over the hub 35 22 is another hub 28, carrying a pinion 29 on its inner end and carrying a face-wheel 30 at its outer end, said face-wheel being so mounted as to be easily operated by the foot of the rider.

40 31 is a rectangular casing inclosing the pinion 29 and hub 28, said casing being held in place by bolts 32. The said casing is cut away at 33, Fig. 3, to allow the teeth of the pinion 29 to protrude from the same and engage with the rack 34, formed on each of the sprocket-wheels 9, which will be presently described.

35 35 is a beveled gear-wheel secured to a flange 36 on the hub 22 by means of the bolts 50 32, and 37 is a horizontal beveled gear-wheel mounted on the vertical journal 38, integral with the forging 17. Lock-nuts 39 hold the said gear-wheel 37 in place.

Each sprocket-wheel 9 is provided with two 55 parallel guides 40 therein. Within each works the rectangular casing 31 before described, and one of said guides 40 is provided with the before-mentioned rack 34, with which the pinion 29 engages. The said guides 40 60 work between the flange 36 on the inside and the flange 41 on the outside, whereby the said sprocket-wheel 9 will be firmly supported. The face-wheel 30 is provided with notches 42 in its periphery, and engaging with said 65 notches is a pin 43, mounted in the operating-lever 26 and being held in constant engagement with the periphery of the face-wheel 30

by means of the small coiled spring 44. This pin 43 may be disengaged from the face-wheel 30 by means of an angular lever 45, attached 70 to a foot-piece 46, adapted to be pressed downward by the foot of the rider. By means of the elements just described the sprocket-wheels 9 may be moved relatively to the journals 18, whereby the relative relation between 75 the length of the crank and the movement of the sprocket-chain 8 may be varied. This adjustment is effected by disengaging the pin 43 from the face-wheel 30, after which said face-wheel may be turned around by the foot 80 of the rider, carrying the pinion 29 with it. This movement of the pinion engaging with the rack 34 will move the sprocket-wheel 9 vertically upward or downward, so as to change the relative relation between said 85 sprocket-wheels and the operating-crank. Upon releasing the lever 45 the pin 43 will again engage with the face-wheel 30 and the parts will be locked together.

The device operates as follows: The operating-levers 26 are operated alternately upward and downward over a path of movement about equal to a quadrant. In moving downward the lever on one side, through the instrumentality of the beveled gear-wheels 35 95 and 37, will elevate the lever at the other side of the machine, the parts being locked together. As will be understood, the sprocket-chains 8 on each side will be moved backward and forward, thereby imparting the same 100 movements to the sprocket-wheels 7, which movements, by reason of the ratchet before described, will give a continuous rotatory movement to the rear driving-wheel. By making use of the spring 16, forming a part of each 105 sprocket-chain, the said sprocket-chains will accommodate themselves to the various positions in which the sprocket-wheels 9 may be placed.

Before claiming my invention I desire to 110 have it understood that I am not to be limited to the particular means described for changing the positions of the operating sprocket-wheels, whereby a different power may be obtained, as that end may be effected 115 in many other ways.

Having now fully described my invention, what I claim as new, and desire to secure by Letters Patent, is—

1. As an improvement in driving gear for 120 bicycles, the combination with the crank levers, the sprocket wheels operated thereby, means for moving said sprocket wheels radially, and pawl and ratchet connections between said sprocket wheels and the driving 125 wheel of the bicycle, substantially as set forth.

2. As an improvement in driving gear for 130 bicycles, the combination with the operating levers and the radially adjustable sprocket wheels connected therewith, of a sprocket chain connecting said sprocket wheels with a rear sprocket wheel, and pawl and ratchet connections between the latter and the driving wheel of the bicycle, substantially as set forth.

3. As an improvement in driving gear for bicycles, the combination with the operating levers and radially adjustable sprocket wheels connected therewith, of the sprocket chains connecting said sprocket wheels with a rear sprocket wheel, pawl and ratchet connection between the latter and the driving wheel of the bicycle, and the coiled spring constituting part of said sprocket chains, substantially as set forth.

4. As an improvement in driving gear for bicycles, the combination with the operating levers and sprocket wheels connected therewith of mechanism for radially adjusting said sprocket wheels, a latch for locking the sprocket wheels and the said operating levers together and pawl and ratchet connections between said sprocket wheels and the driving wheel of the bicycle, substantially as set forth.

5. As an improvement in driving gear for bicycles, the combination with the operating levers and sprocket wheels connected therewith, of a pinion engaging with the rack carried by said sprocket wheel for adjusting the latter vertically, a face wheel for operating said pinion and the latch carried by the said operating levers for engaging with one of said face wheels on each side, substantially as set forth.

6. As an improvement in driving gear for bicycles, the combination with a forging 17, carrying journals 18, of the hub 22, on each of said journals, a pinion 29 mounted on said hubs, a face wheel 30 for operating said pinion and sprocket wheel 9, carrying a rack 34 with which said pinion engages, an operating lever for operating said hub 22 and means for locking the operating lever on each side of the machine with the said face wheel 30, substantially as set forth.

7. As an improvement in driving gear for bicycles, the combination with a forging 17, carrying journals 18, of the hub 22 carried on each of said journals, a pinion 29 mounted on said hub and sprocket wheel 9 carrying a rack 34 with which said pinion engages, a face wheel 30 for operating said pinion, notches 42 in the periphery of said face wheel, operating lever 26 connected with said hub, and the latch 43 carried by said operating lever and engaging with said face wheel, substantially as set forth.

8. As an improvement in driving gear for

bicycles, the combination with a forging 17 carrying a journal 18 on each side, a hub 22 carried on each of said journals, of ball bearings and hub 28 mounted on said hub and pinion 29 on said hub, a sprocket wheel carrying rack 34 with which said pinion engages, a face wheel 30 carried by the hub 28 and operating lever connected with the hub 22, and the latch 43 for locking said operating lever and said face wheel together, substantially as set forth.

9. As an improvement in driving gear for bicycles, the combination with a forging 17 carrying a journal 18 on each side, a hub 22 on each of said journals, a sprocket wheel carried on each side of the machine and means for adjusting said sprocket wheels radially, gear wheels 35 on said hubs and the gear wheel 37 connecting said gear wheels 35 together, for the purpose mentioned of ratchet connections between said sprocket wheels and the rear or driving wheel.

10. In a bicycle, the combination with the journals, the cylindrical hubs having an angular flange near the center, and the cranks secured thereto, of the sprocket wheels having diametric rack bars and slots engaging with said flange, the pinions engaging with said rack bar, the notched wheels secured to the shanks of the pinions, the spring actuated pins carried by the cranks and the levers for operating the same, substantially as set forth.

11. In a bicycle, the combination with the bearing, journals secured thereto, the cylindrical hubs on said journals having angular flanges near the center, and the cranks secured thereto, of the sprocket wheels having diametric rack bars and slots engaging with said flange, the pinions engaging with said rack bars, the notched wheels secured to the shanks of said pinions, the spring actuated pins carried by the cranks, the levers for operating the same, the sprockets and ratchets on the rear axle, the chains connecting the same with the driving sprockets provided with coiled springs, and the intermeshing bevel gears, substantially as set forth.

In testimony whereof I affix my signature in presence of two witnesses.

FRANK HAYES.
